CLAIM

The ornamental design for a condiment cartridge as shown and described.

DESCRIPTION

FIG. 1 is a top perspective view of a condiment cartridge in accordance with our new design;

FIG. 2 is a bottom perspective view of the condiment cartridge of FIG. 1;

FIG. 3 is a front elevation view of the condiment cartridge of FIG. 1;

FIG. 4 is a rear elevation view of the condiment cartridge of FIG. 1;

FIG. 5 is a right-side elevation view of the condiment cartridge of FIG. 1;

FIG. 6 is a left-side elevation view of the condiment cartridge of FIG. 1;

FIG. 7 is a top view of the condiment cartridge of FIG. 1; and,

FIG. 8 is a bottom view of the condiment cartridge of FIG. 1.

The portions of the condiment cartridge shown in broken lines in the figures depict unclaimed environmental subject matter, are for illustrative purposes only, and form no part of the claimed design.

It will be understood that all lines in the drawings, including broken and solid lines, are intended to convey the full disclosure and variations of the designs and such variations shall be understood to be fully described herein. It will also be understood that any and all broken lines (or portions thereof) may be converted to solid lines, and any and all solid lines (or portions thereof) may be converted to broken lines, and any and all boundary lines (if any) may be removed or moved out or in to claim more or less of the condiment cartridge, respectively, whether in subsequent divisional or continuation applications and/or by amendment. In addition, it will be understood that portions of any of the embodiments depicted in the drawings could be pursued on their own in later divisional or continuation applications and/or by amendment.
